UNITED STATES PATENT OFFICE.

WILLIAM B. PURVIS, OF PHILADELPHIA, PENNSYLVANIA.

ELECTRIC RAILWAY.

SPECIFICATION forming part of Letters Patent No. 655,455, dated August 7, 1900.

Application filed April 24, 1900. Serial No. 14,091. (No model.)

To all whom it may concern.

Be it known that I, WILLIAM B. PURVIS, a citizen of the United States, residing in the city and county of Philadelphia, in the State 5 of Pennsylvania, have invented a new and useful Improvement in Electric Railways, which improvement is fully set forth in the following specification and accompanying drawings.

10 My invention consists of an improved construction of an electric-railway system, as hereinafter fully described and claimed.

Figure 1 represents a vertical longitudinal section of an electric railway constructed in 15 accordance with my invention and taken on the line *y y* of Fig. 2. Fig. 2 represents a vertical transverse section taken on the line *x x*, Fig. 1. Fig. 3 represents a fragmentary view in side elevation and section, illustrating the means for preventing the accumulation of moisture within the conduit. Fig. 4 represents a vertical transverse section of a modified construction embodying my invention.

25 Similar letters of reference indicate corresponding parts in the figures.

Referring now particularly to Figs. 1 and 2 of the drawings, *A* designates my improved conduit, which is of non-conducting material, 30 being preferably wood suitably treated to be damp-proof. The said conduit *A* is embedded in the road-bed *B*, which is preferably asphalt or other approved material, and at one side thereof the sections of the third rail *C* are 35 mounted, said sections of the third rail *C* projecting above the road-bed *B* in the usual manner. The upper side of the conduit *A* is provided with a longitudinal channel or groove that consists of an upper section *D* to 40 receive the cover *E*, the main-feeder section *F*, in which the main feeder *G* of the electric-railway system is situated, and the lower section *H* to receive water and moisture that may accumulate within the channel of the 45 conduit. The cover *E* is also of non-conducting material, as well as non-magnetic material, and is provided at its upper side with embedded plates *J*, of non-magnetic material and which is an electric conductor. On the 50 lower side of these covers *E* are similar plates *K*, said plates *J* and *K* being fastened by

means of bolts *L*, of conductive material, that extend through the cover *E*. It is understood, of course, as shown in Fig. 1, that said plates *J* and *K* are arranged in insulated sections corresponding to the sections of the third rail *C*, and corresponding sections of said plates *J* and third rail *C* are connected by conductors *C'*. The said third rail *C* is mounted upon a longitudinal elevation of the conduit 55 *A*, which forms a shoulder or lateral projection, against which fit the blocks of non-magnetic material *M*, which rest upon the upper side of the conduit *A* and whose upper faces are flush with the road-bed *B*. (Shown in 60 Fig. 2.)

The car is designated by *N* and is provided with a current-collector *P* and magnet *Q* of familiar construction.

The main feeder or cable *G* differs from the 70 cable heretofore used in these systems of electric railways in that instead of being round—for instance, as shown in Letters Patent granted to myself May 1, 1894, No. 519,291—it is flat and is composed of a series 75 of connected wire coils—for instance, somewhat on the order of wire mattress fabric. This flat main feeder has an extended surface to be acted upon by the magnet on the car, which increases the certainty and exact- 80 ness of the operation thereof.

In Fig. 3 I have shown means for preventing the accumulation of moisture within the conduit. Although the conduit *A* is made damp-proof as far as practical and is inclosed 85 on all sides by suitable moisture-proof and insulating material, yet there may be an accumulation of moisture within the conduit, which of course is objectionable, and to obviate this I propose to pass through the conduit dry air to carry off such moisture. In 90 said Fig. 3 the end sections of the conduit *A* are shown. At one end said conduit is connected with the chamber *R*, containing a suitable solution to deprive air of this moisture. 95 A pipe *S* leads to the bottom portion of said chamber, and the other end of the conduit is connected with an air-forcing device *T*, which when in operation creates a current, as indicated by the arrows, to draw air in through 100 the pipe *S* and deprive it of its moisture in passing through the solution in the chamber

R and then pass it through the conduit as dry air to take up and carry off any moisture which may accumulate therein.

It is understood, of course, that by constructing a conduit so that there is only non-magnetic material between the main feeder and the magnets of the car the maximum of the magnetism is utilized, since the lines of force on the magnet pass through non-magnetic material and are absorbed only by the cable G or main feeder.

In the construction shown in Fig. 4 the third rail is mounted upon a separate base or foundation-piece and is connected with the contact-plates in the conduit by suitable electric connections, which may contain a safety-fuse.

Having thus described my invention, what I claim as new, and desire to secure by Letters 20 Patent, is—

1. In an electric-railway system, a closed conduit containing a flexible main feeder, a third rail electrically connected with terminals situated within said conduit and adapted 25 for contact with said main feeder, the covering for said conduit and the material of said conduit situated above said main feeder being composed of non-magnetic material.

2. A conduit for an electric-railway system, 30 consisting of a base of non-magnetic and non-conducting material having a longitudinal channel in its upper side, a flexible main feeder within said channel, a cover for said channel composed of non-magnetic material, 35 conducting-plates of non-magnetic material

situated on the upper and lower faces of said cover, and a third rail electrically connected with the upper conducting-plate.

3. In an electric-railway system, a closed conduit, a flexible main feeder therein, terminals within said conduit adapted for contact with said main feeder, and a contact-rail connected with said terminals, the portion of said conduit situated above said main feeder being non-magnetic. 40

4. In an electric-railway system, a closed conduit having its upper side composed of non-magnetic and non-conducting material, a flexible main feeder in said conduit, terminals within said conduit adapted for contact 45 with said main feeder, and a contact-rail connected with said terminals.

5. In an electric-railway system, a conduit having a base of non-magnetic and non-conducting material provided with a channel in 55 its upper side, a flexible main feeder in said channel, a cover for said channel of non-magnetic and non-conducting material, terminals within said conduit adapted for contact with said main feeder, a contact-rail 60 mounted upon said base and connected with said terminals, and blocks mounted upon said conduit, said conduit, contact-rail and blocks being embedded in a suitable road-bed with the upper side of the contact-rail and blocks 65 exposed.

WILLIAM B. PURVIS.
